UNITED STATES PATENT OFFICE.

FRANK D. BERRY, OF NEW YORK, N. Y.

EGG CARTON.

Application filed October 6, 1927. Serial No. 224,388.

My invention relates to improvements in egg cartons of the type consisting of a cell-forming filler enclosed in a wrapper, and resides particularly in improvements in the wrapper.

It has been proposed to make such wrappers of a blank of cardboard material having transverse bending corrugations and longitudinal corrugations for locking the 10 filler in place. These wrappers are open to two objections; namely, that in the formation of the corrugations the material is fractured because of the inability of cardboard to stretch, and that, after formation, since 15 the corrugations intersect, it is impossible to bend on the bending line because of the fact that the cardboard at the longitudinal corrugation must stretch in order to allow the bending, and since it cannot, it will resist 20 bending or break.

My invention comprises a joint at the intersection of the longitudinal and transverse corrugations whereby the longitudinal corrugation will contain more paper at the 25 point of intersection with the transverse corrugation than previously has been the case so that when the wrapper is bent on the transverse corrugation the excess paper in the longitudinal corrugation will compensate for the bending. But since in the formation of such joints as well as in the formation of the corrugations, the paper is subjected to the same stresses as in the prior 30 art, it is open to the same objection as are the devices of the prior art.

My invention therefore contemplates the manufacture of such wrappers from a plurality of plies of expansible paper of which the common type is crepe paper. In manufacturing from this type of paper the paper 40 is bound in superimposed layers with waterproof glue such as silicate of soda, and while the glue is still wet, the paper is subjected to an embossing operation heat being simultaneously applied. The object of embossing while the glue is wet is to take advantage of the fact that, in that state, there 45 will be slippage between the various plies so that allowance can be thereby made for the greater expansion necessary for the material on the outside of the convexed surfaces. If no slippage were allowed the outside layers would have to stretch more than the inside layers and might be broken. Furthermore, the fact that the paper is expansible

permits all the layers to stretch over curved surfaces. This fact is due, of course, not to stretching of the paper, but rather to the smoothing out of the crinkles that are present in creped paper. The finished article 60 presents a substantially smooth appearance.

My invention further contemplates the provision of egg supporting embossed portions on the top and bottom portions of the wrapper to positively hold the egg between 65 them.

My invention further contemplates the slitting of the ends of the bending lines of the wrapper, thereby allowing the side edges of the wrapper to be turned in over the ends 70 of the filler, to hold the filler from longitudinal motion.

It must be noted that, as before stated, the fact, that paper will not stretch, renders it useless for the manufacture of wrappers 75 involving embossing in two directions for the reason that it will inevitably break and render the product undesirable for use. I have found, after exhaustive research, that the use of the above described multi-ply expansible paper is the only means by which 80 such objections can be overcome. Wrappers made according to my invention are strong, flexible, light, cheap and weather-proof.

My invention further contemplates such improvements and advantages as will appear from the following detailed description of the drawings in which:-

Fig. 1 is a perspective view of the wrapper in use.

Fig. 2 is a cross-section along the line 2-2 of Fig. 1 with the wrapper completely folded.

Fig. 3 is a longitudinal section along 3-3 of Fig. 1 with the wrapper folded.

Fig. 4 is a section through one of the bending joints.

Fig. 5 is a plan view of the wrapper in open position.

Fig. 6 is a section through the line 6-6 of Fig. 5.

Fig. 7 is a section through the line 7-7 of Fig. 5.

Fig. 8 is a detail of the wrapper showing 105 the multi-ply construction.

Referring to the drawings in particular, Fig. 1 shows an egg carton consisting of a cell-forming filler 1 made up of transverse walls 2 having vertical slits in the center 110

and adjacent both ends, and longitudinal walls 3 of less height than the transverse walls, and having vertical slits at intervals whereby each longitudinal wall may be connected with a plurality of transverse walls by mutual engagement of the slits. When assembled the transverse walls project beyond the longitudinal walls at the top and bottom and sides. This cell-forming structure is enclosed by a wrapper 4 shown more clearly in Fig. 5 wherein 5 are outwardly embossed transverse corrugations, and 6 are outwardly embossed longitudinal corrugations. At the points of intersection of said corrugations are inwardly pressed concavities shown in section in Figs. 4 and 6. Because of the concavities when the wrapper is bent, the outer layer of the longitudinal corrugation which would ordinarily be subjected to the greater stress is not subjected to any stress. Referring to Fig. 5 it will be seen that the wrapper is divided by the bending lines into bottom portion 8, top portion 9, end portions 10, and flap 11. All these portions are divided into sections by the longitudinal corrugations which are equal in number to the transverse walls of the cell-forming filler and in position to receive the edges of said walls when said cell-forming filler is enclosed by the wrapper.

In each of the sections of the top and bottom portions set off by such longitudinal corrugations are a pair of egg supporting embossed portions 12 in similar positions. These egg supporting portions as shown in section in Fig. 3 consist of convexed portions 13 pressed inwardly, the centers of which are concaved, forming pockets 14 for receiving ends of eggs. The end portions of the bending corrugations 5 are slit as at 15 whereby when the wrapper is folded the side edges thereof may be bent inwardly as shown in Fig. 3 to form stops for the enclosed filler. The wrapper has at its extreme ends, corresponding slits and tongues to provide closure means in the well-known manner.

The wrapper as shown in Fig. 8 is made of three plies of material, A, B and C. The center ply is usually heavier than the outer plies, but may be of the same weight. Whatever be the weight of the plies, which is a matter of choice, they all must be of expandable paper such as crepe paper in order that the product will be satisfactory. The number of plies may be increased as desired.

The ordinary method of making the wrapper is to supply the plies of paper from separate rolls, coat both sides of the inner plies with glue, preferably sodium silicate solution, collate the plies by passing them in superimposed relation between presser rollers, cut the laminated structure so formed into desired lengths, place each length on an embossing plate while the glue is still wet

and emboss thereon the desired portions, at the same time applying heat whereby the wrapper is stiffened in embossed form.

In using the wrapper in connection with a filler, the filler is placed on the bottom portion with its transverse walls in the longitudinal corrugations 6, the end walls 10 are bent upwardly with their corrugations engaging the side edges of the transverse walls of the filler, eggs are placed on end in the egg supporting portions of the bottom, the top is brought down with its corrugations 6 engaging the upper edges of the transverse walls of the filler, and its egg supporting portions engaging the top ends of the eggs, the flap is closed and the side edges of the wrapper are turned inwardly as shown in Fig. 3.

As can be seen, by the use of my wrapper, the eggs are positively held from contact with any surface and with each other, and the filler is locked in place and cannot be propelled from the side of the closed wrapper by a sudden thrust in that direction, to which thrust such a carton is frequently subjected, because of the turned in side portions of the wrapper.

Having thus fully described and explained the manufacture, construction and advantages of my device, what I wish to claim as new and protect by Letters Patent is:—

1. In an egg carton made up of a cell forming filler enclosed in a wrapper, a wrapper having intersecting corrugations, said wrapper being made up of a plurality of plies of expandable paper adhesively secured in superimposed relation.

2. In an egg carton made up of a cell forming filler enclosed in a wrapper, a wrapper having top, bottom, and side portions, and a plurality of inwardly directed egg supporting members on said bottom portion, each comprising a convex embossed portion having a concavity at its center, said wrapper being made up of a plurality of plies of expandable paper adhesively secured in superimposed relation, and said egg supporting members being embossed on the composite plies.

3. In an egg carton made up of a cell forming filler enclosed in a wrapper, a wrapper comprising a blank made of a plurality of plies of expandable paper and having outwardly embossed corrugations running longitudinally and transversely thereof, the points of intersection of said corrugations being pressed inwardly to form unbreakable bending points.

4. In an egg carton made up of a cell forming filler enclosed in a wrapper, a wrapper having longitudinal outwardly embossed corrugations forming locking means for the transverse walls of the cell-forming filler and bending lines comprising transverse outwardly embossed corrugations in-

tersecting said longitudinal corrugations, the points of intersection of said corrugations being concaved whereby such points will not break when the blank is bent on its bending lines.

5. In an egg carton made up of a cell-forming filler enclosed in a wrapper, a wrapper consisting of a blank having transverse bending lines dividing it into top, bottom and side portions and comprising outwardly embossed corrugations, longitudinal outwardly embossed corrugations forming locking means for the transverse walls of the enclosed filler, and concavities at the intersections of the bending and locking corrugations whereby breakage at such points when the blank is bent is prevented.
10. In an egg carton made up of a cell-forming filler enclosed in a wrapper, a wrapper consisting of a blank having transverse bending lines dividing it into top, bottom and side portions and comprising outwardly embossed corrugations, longitudinal outwardly embossed corrugations forming locking means for the transverse walls of the enclosed filler, and concavities at the intersections of the bending and locking corrugations whereby breakage at such points when the blank is bent is prevented.
15. In an egg carton made up of a cell-forming filler enclosed in a wrapper, a wrapper consisting of a blank having transverse bending lines dividing it into top, bottom and side portions and comprising outwardly embossed corrugations, longitudinal outwardly embossed corrugations forming locking means for the transverse walls of the enclosed filler, and inwardly embossed egg supporting portions on the top and bot-

tom portions, said blank being made up of a plurality of plies of expandible paper adhesively secured in superimposed position whereby the embossed portions may be formed without rupturing the said blank.

7. In an egg carton made up of a cell-forming filler enclosed in a wrapper, a wrapper comprising a blank having bending lines dividing it into top, bottom and side portions and a flap, outwardly embossed longitudinal corrugations forming locking means for the transverse walls of the cell-forming filler, said bending lines consisting of outwardly embossed corrugations which intersect the longitudinal corrugations, and inwardly embossed concavities at the points of intersection whereby breakage at such points is prevented when the blank is bent, said blank being wider than the length of said filler and having the ends of its bending lines slit whereby when the filler is enclosed therein the side edges of the wrapper may be turned inwardly to lock the filler from longitudinal motion.

In testimony whereof I have hereunto set my hand.

FRANK D. BERRY.
